MACHINE FOR SHAPING UPPERS
OVER LASTS

Roy W. Cummings and Lloyd G. Knowles, Beverly, and Andrew Eppler, Jr., Swampscott, Mass., assignors to United Shoe Machinery Corporation, Paterson, N. J., a corporation of New Jersey

Application December 14, 1933, Serial No. 702,412

43 Claims.

(Cl. 12—7)

This invention relates to machines for use in the manufacture of shoes, and more particularly to machines having means for shaping shoe upper materials over lasts. The invention is herein shown as embodied in a machine having means for lasting the opposite sides of shoes between their toe and heel-end portions, and adapted more particularly for operating upon shoes in the manufacture of which the upper materials at 5 the opposite sides are secured in lasted position by cement, although it will be understood that the invention is not limited to the manufacture of that kind of shoe, nor limited in respect to the portion of the shoe upon which the operation is 10 performed.

In the illustrated machine there is provided, in accordance with a feature of the invention, a novel organization of means for shaping uppers over lasts comprising a flexible lasting device, 20 herein shown as a rubber apron which by engagement with the upper from its toe-end portion to its heel-end portion draws the upper tightly over the last, and fluid pressure means for conforming said lasting device to the shape of the 25 last as the upper is worked over the last and for thereafter operating it to lay the marginal portion of the upper inwardly over an insole on the last and to press it upon the insole. In the construction shown, the rubber apron is arranged to support a last presented by the operator bottom upward with an upper and an insole thereon and is, in turn, supported at opposite sides of the last by carriers which are movable bodily upward, by power operated means, to 30 stretch the apron over the last and thus to cause it by frictional contact with the upper to draw the upper tightly over the last. As herein shown also these carriers are movable inwardly over the insole, at the completion of their upward movements, about an axis located below the last to increase the tension of the apron about the upper and last, the last being supported, in the illustrated construction, against the pull of the apron by holdowns arranged to engage the bottom 35 face of the insole at opposite ends of the last.

For purposes of the present invention the rubber apron, as herein shown, is chambered at opposite sides of the last to receive fluid under pressure and to be expanded thereby and is provided 40 with upper-pressing portions which, as the apron is expanded, act to press the upper into conformity to the shape of the last, the fluid pressure means acting, as the apron is stretched heightwise of the last, progressively to increase 45 the pressure of the apron on the upper and thus

to increase its frictional pull on the upper. In order to render the fluid pressure means effective to operate the apron in such manner as to lay the marginal portion of the upper inwardly over the insole and to press it upon the insole firmly enough to adhere to the insole, there is provided, in accordance with a further feature of the invention, means movable into position over the insole to enclose the upper portions of the apron and thus to confine it against excessive expansion 10 heightwise of the last away from the insole. As illustrated, this means comprises members arranged to be moved by the above-mentioned carriers inwardly over the insole into interlocking relation to each other so that the upper-pressing 15 portions of the apron, as the apron is expanded by the fluid pressure, will stretch inward to lay and press the marginal portions of the upper effectively upon the insole.

The invention further provides novel means 20 operative by fluid pressure to clamp the upper to the sides of the last near the top of the last so as to prevent distortion of these portions of the upper heightwise of the last as the upper is drawn tightly over the last. As shown, the elastic apron is provided with a lower portion arranged to extend across the top face of the last, this lower portion being chambered and expandable by fluid pressure to press the upper near the top face of the last against the last. For preventing excessive expansion of the chambered 25 lower portion of the apron in directions away from the last there is provided, in the construction shown, a rigid member shaped similarly to and arranged to engage the lower portion of the 30 apron.

In accordance with another feature of the invention, there is provided automatic means for controlling the admission of pressure fluid to the expandable apron and release of the fluid therefrom. The machine herein shown is provided with conduits connected to the upper and lower chambers of the apron and with a pair of levers connected by conduits to a source of supply of pressure fluid, these levers being provided with 45 valves held normally in closed positions but arranged to be opened by means carried by the first-named conduits as the levers are swung in directions to connect the conduits together. As illustrated, the construction is such that the levers are held normally with the conduits disconnected, automatic means being provided for imparting to the levers their swinging movements to connect the conduits together and open the valves substantially at the beginning of the upward move- 50 55

ments of the carriers. In accordance with another feature of the invention there is provided means for regulating the flow of pressure fluid to the upper chambers of the apron, this means being herein shown as a valve adjustable to permit sufficient pressure fluid to be admitted to the upper chambers of the apron to expand the apron into conformity to the shape of the last and thus progressively to increase the pressure of the apron on the upper and its frictional pull on the upper as the carriers are lifted, without causing any substantial stretching of the upper pressing portions of the apron at this stage in the operation of the machine. The machine herein shown is constructed to utilize compressed air as the pressure fluid, although it is to be understood that the invention is not limited to the use of fluid of that character.

The above and other features of the invention, including various novel details of construction and combinations of parts, will now be more particularly described by reference to the accompanying drawings and pointed out in the claims.

In the drawings,

Fig. 1 is a view partly in front elevation and partly in section of a machine in which the invention is embodied, showing the machine as it appears at an intermediate stage in the cycle of operations;

Fig. 2 is a section of the line II—II of Fig. 1;

Fig. 3 is a view in rear elevation, on an enlarged scale, of a portion of the pressure fluid controlling means;

Fig. 4 is a section on the line IV—IV of Fig. 3;

Fig. 5 is a section on the line V—V of Fig. 2 showing the positions of the parts at the completion of the upper tensioning operation; and

Fig. 6 is a view similar to Fig. 5, illustrating the positions of the parts with the shoe under pressure at the completion of the lasting operation.

For lasting the opposite sides of shoes the machine herein shown is provided with a lasting member or apron 20 of flexible elastic material, preferably rubber, which is suspended from a pair of carriers or levers 22, 24 to form a sling-like support for a last presented by the operator bottom upward with an upper and an insole thereon. The apron 20 is secured to the upper ends of the carriers 22, 24 by clamps 26, 28 and clamp screws 30, 32, the clamps being also secured to the carriers by screws 34, 36. As shown particularly in Fig. 2, the apron 20 is arranged to extend across the top face of the last and to engage the upper at opposite sides of the shoe between its toe and heel-end portions which may be and, as illustrated, have been lasted before the shoe is presented to the machine. For purposes of this invention the apron 20 is provided with a lower chamber 38 and with upper chambers 42, 44, Figs. 1, 5 and 6, for receiving fluid under pressure, the lower chamber 38 being separated at opposite sides of the shoe from the upper chambers 42, 44 by ribs 46 which extend lengthwise of the shoe at opposite sides thereof just above the top face of the last and, as shown, are shaped somewhat in accordance with the longitudinal curvature of the bottom of the last. The lower and upper chambers of the apron 20 have connected thereto respectively flexible pipes or conduits 48, 50 through which the pressure fluid is admitted and exhausted in time relation to other operations by means which will presently be described.

In the operation of the machine the flexible elastic apron 20 is moved heightwise of the last,

by means hereinafter described, to cause it by frictional contact with the upper to draw the upper tightly over the last which is supported against the upward pull of the apron by hold-downs 52, 54 arranged to engage the bottom face 5 of the insole and the overlaid margin of the upper at the opposite ends of the last. The hold-downs 52, 54 are pivotally connected respectively to the lower ends of rods 56, 58 which are slidably mounted for movements in directions heightwise 10 of the last in blocks 60, 62 slidably mounted for movements in directions lengthwise of the last in a bracket 64 which is secured to the frame 67 of the machine. Surrounding the rods 56, 58 between the blocks 60, 62 and heads 66, 68 formed 15 on the upper ends of the rods, are springs 70, 72 which tend to urge the rods upwardly. Pivotally connected to the blocks 60, 62, respectively, are pawls 78, 80 which are spring urged in directions 20 to engage any one of a number of ratchet teeth 82, 84 formed respectively on the rods 56, 58 and to lock the hold-downs 52, 54 in engagement with the bottom face of the shoe. The pawls 78, 80 are each provided with an outwardly and upwardly extending tail portion 86 by means of 25 which they may be swung by the operator out of engagement with the ratchet teeth to permit the springs 70, 72 to move the hold-downs upwardly away from the shoe bottom. A rod 88, having oppositely threaded portions, extends through the 30 blocks 60, 62 and has secured to its outer end a hand wheel 90 by means of which it may be rotated to move the blocks 60, 62 and the hold-downs 52, 54 toward or from each other in directions lengthwise of the shoe to accommodate shoes 35 of different sizes.

The carriers 22, 24 to which the upper ends of the apron 20 are clamped are pivoted at 92 below the apron, Figs. 1 and 2, to levers 94 which are fulcrumed at 96 to the frame 67 of the machine. Each lever 94 carries a cam roll 100 which is arranged to engage a power cam 102 formed on a cam wheel 104 fast to a cam shaft 106 mounted in suitable bearings in the frame 67. The configuration of the cams 102 is such that 40 at a predetermined time in the cycle of the shaft 106 the levers 94 are swung in a counterclockwise direction (Fig. 1) to move the carriers 22, 24 upwardly and with them the apron 20 heightwise of the last. As the apron 20 is moved heightwise of the last it is stretched more or less over the last and thus acts through frictional contact with the upper at opposite sides of the last to draw or tension the upper over the last and to work it toward the edge of the insole. Substantially at the beginning of the upward movement of the apron, as hereinafter more fully explained, it is expanded somewhat by the admission of pressure fluid to its upper chambers 42, 44 to cause the apron to press the upper better at 50 opposite sides of the last into conformity to the shape of the last and to increase the friction between the apron and the upper. At the same time pressure fluid is admitted to the lower chamber 38 to cause the apron to clamp the upper near the top of the last against the sides of the last to prevent distortion of these portions of the upper heightwise of the last. In order that the fluid pressure means will be immediately effective to conform the apron 20 to the shape of 55 the last, the lower and upper chambers of the apron are provided respectively with relatively thin upper pressing walls 45, 47 (Figs. 1, 5 and 6). To prevent excessive expansion of the apron 20 in directions away from the last as its lower 60

chamber 38 is expanded, there is secured to the frame 67 a bracket 65 provided with a rib 98 which is shaped similarly to the lower portion of the apron and extends upwardly at opposite sides of the apron as far as the ribs 46.

Each carrier 22, 24, Fig. 1, has pivotally connected to it at 112, one member 114 of a toggle the other member 116 of which is pivotally connected at 118 to the frame 67. The toggle members 114, 116 are pivotally connected at 120 to each other and to the upper end of a link 122 the opposite end of which is pivotally connected at 124 to one end of a lever 126. Each lever 126 is fulcrumed at 128 to the frame of the machine 15 and carries a roll 130 which is arranged to engage a path cam 132 formed in the cam wheel 104. As the carriers 22, 24 move upwardly the cams 132 act to swing the levers 126 about their fulcrums to impart upward movement to the links 20 122 to prevent the carriers 22, 24 from swinging outwardly, after which, as the carriers 22, 24 complete their upward movements, further swinging movements in the same direction are imparted to the levers 126 by the cams 132 to 25 straighten the toggles 114, 116 and thus to impart inward swinging movements to the carriers. Since the carriers are pivoted for swinging movements about an axis located below the last supported by the apron 20, the apron is additionally 30 tensioned heightwise of the last as the carriers 22, 24 are swung toward each other to carry the upper ends of the apron inwardly over the insole. As the carriers 22, 24 are swung inwardly from the positions shown in Fig. 1 to the positions 35 shown in Fig. 5 the clamps 26, 28 which, as shown, are provided with interlocking edges, act to enclose the upper ends of the apron 20 and thus to confine it against excessive expansion in directions heightwise of the last away from the 40 insole when the fluid pressure means acts, as more fully explained hereinafter, to operate the apron to lay the marginal portion of the upper, at opposite sides of the last, inwardly over the insole and to press it upon the insole.

55 The flexible conduit 48 is connected at its upper end to a duct 134 leading to the lower chamber 38 of the apron 20 (Fig. 2). At its lower end the conduit 48 is secured to the upper end of a tube 138 which is threaded into a block 140 secured to the frame of the machine. The block 140 is provided with a passage 141 arranged to connect the tube 138 with a second tube 142 which extends outwardly beyond the outer face of the block 140 and is surrounded by a rubber gasket 144, Fig. 3. The flexible conduits 50 are connected at their upper ends to ducts 136 which lead to the upper chambers 42, 44 of the apron. In order that fluid under pressure may be admitted simultaneously to the upper chambers 42, 60 44, there is threaded into the block 140, Figs. 3 and 4, a tube 146 having a pair of upwardly extending arms 148 to which the lower ends of the conduits 50 are secured. As shown, particularly in Fig. 4, the block 140 is provided with a passage 143 from which extends beyond the outer face of the block a tube 145, which tube is surrounded by a rubber gasket 147. A second passage 149 in the block 140 connects with the tube 146 and is separated from the passage 143 by an 65 inclined rib 151. A port 153 in the rib 151 is arranged to serve as a seat for a needle valve 155 which may be adjusted toward or from the seat (to regulate the flow of pressure fluid through the conduits 50 to the upper chambers 42, 44 of the apron 20) by a threaded spindle 157. The spindle

157 is provided with a knurled head 159 for turning it and extends through a nut 161 threaded on the upper end of a boss 163 on the block 140. Between the upper surface of the boss 163 and the nut there is provided a leather washer 5 165. From the above description it will be seen that by adjustment of the needle valve 155 the flow of pressure fluid through the conduits 50 to the upper chambers 42, 44 of the apron may be regulated to control the rate of expansion of 10 the upper chambers of the apron.

For controlling the admission and exhaustion of air under pressure to and from the chambers 38, 42, 44 of the apron 20 through the flexible conduits 48, 50, there are provided, Figs. 2 and 3, 15 a pair of levers 150, 152 pivoted at 154, to the frame of the machine and having downwardly extending arms 156, 158 carrying rolls 160, 162 arranged to engage power cams 164, 166 formed in a cam member 168 which is fast to the outer 20 end of the cam shaft 106. Each lever has an upwardly extending arm 170, Fig. 4, provided with a passage 172 connected by a flexible conduit 173 to a supply of compressed air and each passage 172 is closed at its inner end by a valve 174. As 25 shown, each valve 174 has a stem 176 which is surrounded by a rubber washer 177 the inner side face of which forms a seat for the valve. At a predetermined time in the cycle of the shaft 106 the cams 164, 166 act to swing the levers 150, 152 toward the block 140 and to press them 30 against the rubber gaskets 144, 147 which surround the projecting ends of the tubes 142, 145 in the block to provide air-tight joints. As the levers 150, 152 are swung toward the block 140 35 the valves 174 are opened by the engagement of their stems 176, with pins 178 carried by the tubes 142, 145 (Fig. 4) thereby permitting air under pressure to be admitted to the chambers 38, 42, 44 of the apron 20 through the flexible 40 conduits 48, 50. As the levers 150, 152 are swung in the opposite directions the tubes 142, 145 are uncovered thereby permitting the air to be exhausted from the chambers of the apron, each valve 174 being closed as the levers 150, 152 are 45 swung away from the block 140 by the pressure of the air in the passage 172, against a shoulder 180 on the valve.

For operating the cam shaft 106 there is provided a driving shaft 182 to which there is secured a sleeve 184 carrying a gear 186 the teeth of which mesh with the teeth of a gear 188 formed on the rear cam block 104. The driving shaft 182 is supported at the front of the machine by a bearing 190 carried by the frame 67 and at the rear of the machine by a bracket 192 which is secured to the frame 67 by clamp screws 194 and is provided with a rearwardly extending hollow spindle 196 through which the shaft 182 extends. Rotatably mounted on the spindle 196 is a pulley 200 which is connected by a belt 202 to a pulley 204 continuously driven by an electric motor 206 mounted within the frame 67 of the machine. The pulley 200 is formed to serve as one member of a clutch the other member 208 of which is fast to the outer end of the driving shaft 182. The bracket 192 has formed thereon a brake surface 210 which is arranged to be engaged, when the machine is to be stopped, by a brake disk 212 60 carried by the sleeve 184. The sleeve 184 is provided with a circumferential groove 214 arranged to be engaged by rolls 216, 218, Fig. 1, carried by the depending arms 220, 222, of a lever 224 loosely journaled on a shaft 226 which is mounted in 65 70 75

bearings in the frame 61 and extends transversely of the machine between the driving shaft 182 and the cam shaft 106, Fig. 2. A spring 228 connected at one end to the frame of the machine and at the other end to the arm 220 of the lever 224 tends to swing the lever 224 in a direction to move the sleeve 184 and driving shaft 182 forwardly and to hold the clutch members 200, 208 in engagement. Pivotally connected to the arm 222 of the lever 224 is a latch 230 which is connected by a link 232 to a treadle 234 fulcrumed at 236 to the base of the machine. A spring 238 connected at one end to the treadle and at the other end to the base acts, when permitted, to swing the treadle upwardly and to hold the latch 230 in operative relation to the downwardly extending arm 240 of a lever 242 fast to the shaft 226. The lever 242 has an upwardly extending arm 244 carrying a roll 246 arranged to engage a power cam 248 fast to the cam shaft 106. The configuration of the cam 248 is such that near the end of the cycle of the cam shaft 106 a sufficient clockwise movement, Fig. 2, is imparted to the lever 242 to permit the spring 238 to move the latch 230 upwardly into operative relation to the end of the arm 240 of the lever 242, after which the cam 248 acts to swing the lever 242 in a counterclockwise direction and to move the lever 224 through the latch 230 in a direction to impart rearward movement to the sleeve 184 and the shaft 182 thereby disconnecting the clutch members 200, 208 and moving the brake disk 212 into engagement with the brake surface 210 to stop the operation of the machine at the end of the cycle of the cam shaft 106. Depression of the treadle 234 acts to swing the latch 230 downwardly out of engagement with the end of the arm 240 to permit the spring 228 to swing the lever 224 in a direction to impart forward movement to the sleeve 184 and the shaft 182, thereby moving the brake disk 212 out of engagement with the brake surface 210 and moving the clutch member 208 into engagement with the driving clutch member 200 to start the operation of the machine.

In the operation of the machine briefly summarized, the operator, after adjusting the lengthwise positions of the holdowns 52, 54 for the size of shoe to be operated upon, places a last 50 and shoe in the apron 20 and lowers the rods 56, 58 to move the holdowns into engagement with the opposite ends of the shoe. Before the shoe is presented to the machine, in accordance with the illustrated practice, its toe and heel ends 55 will have been previously lasted and a suitable adhesive, such as latex or pyroxylin cement, will have been applied to the margins of the upper materials and also, if desired, to the margin of the insole along the opposite sides of the shoe.

60 After the shoe has been mounted in the machine as above described the operator depresses the treadle 234 to move the latch 230 out of engagement with the downwardly extending arm 240 of the lever 242 to permit the spring 228 to move the sleeve 184 forwardly to start the operation of the machine. At the beginning of the operation of the machine the carriers 22, 24 are moved bodily upward by the action of the cams 102 on the levers 94 to move the apron relatively 65 to the last in a direction heightwise of the last, the apron being stretched somewhat as it is moved upwardly so that it acts by frictional contact with the upper to draw the upper tightly over the last. It will be understood that the shoe and last are 70 held against the upward pull of the apron by the

holdowns 52, 54 which are locked in shoe supporting positions by the pawls 78, 80. Substantially at the same time the cams 164, 166 act to swing the levers 150, 152 toward the block 140 to connect the conduits 173 with the conduits 48, 50 and to open the valves 174 to permit air under pressure to be admitted simultaneously to the chambers 38, 42, 44 of the apron 20. It will be understood that the flow of pressure fluid to the upper chambers 42, 44 of the apron may be controlled by adjustment of the needle valve 155. Preferably the needle valve is so adjusted that sufficient pressure fluid will be admitted to the upper chambers 42, 44 at the beginning of the upward movement of the apron to insure effective frictional engagement of the apron with the upper and to cause it to press the upper into conformity to the sides of the last. Thereafter, during the further upward movement of the apron the pressure fluid serves progressively to increase the pressure of the apron on the upper and thus to increase its frictional pull without causing the upper pressing walls 47 of the upper chambers to stretch inwardly over the insole to any substantial extent. 25

As the apron 20 is stretched by the upward movement of the carriers 22, 24, the fluid pressure means acts through the apron in the lower chamber 38 to clamp portions of the upper near the top of the last against the sides of the last 30 with sufficient pressure to prevent distortion of these portions of the upper heightwise of the last. Substantially at the time when the carriers 22, 24 complete their upward movements they are swung inwardly by the straightening of the toggles 114, 35 116 through the action of the cams 132 on the levers 126. As the carriers move inwardly the apron 20 is additionally stretched over the last as its upper ends are carried inwardly over the insole and enclosed by the clamps 26, 28 which are 40 moved into interlocking relation with each other by the inward movements of the carriers, the clamps thus acting to confine the apron against excessive expansion heightwise of the last in directions away from the insole. It will be seen 45 that as the apron is additionally tensioned over the last by the inward movements of the carriers 22, 24, the tension of the upper over the last is increased as it is drawn more tightly over the rounded lateral faces of the last. After the 50 clamps 26, 28 have been moved into interlocking relation with each other (Fig. 5), continued expansion of the apron causes the upper-pressing walls 47 of the upper chambers 42, 44 to stretch inward to lay the marginal portion of the upper 55 inwardly over the insole in position to adhere thereto through the action of cement and to press it firmly upon the insole as shown in Fig. 6. After the upper chambers 42, 44 of the apron have been fully expanded to press the marginal portion of the upper into firm adherence to the insole, the levers 150, 152 are swung by the cams 164 and 166 in a direction to uncover the tubes 142, 145 in the block 140 to permit release of the pressure fluid from the upper and lower chambers of the apron, 60 after which the cams 132 act to swing the levers 126 downwardly to break the toggles 114, 116 and thus to swing the carriers 22, 24 outwardly. The cams 102 are so shaped that after the carriers 22, 24 have been moved outwardly they are permitted to be moved downwardly by the elasticity of the apron 20. The operator then swings the pawls 78, 80 outwardly to unlock the rods 56, 58 and to permit the springs 70, 72 to move the holdowns 52, 54 upwardly to release the shoe so that 75 70 75

it may be removed from the machine. The machine is finally brought to a stop in a starting position by the action of the cam 248.

Having described our invention what we claim 5 as new and desire to secure by Letters Patent of the United States is:

1. In a lasting machine, a device arranged to act frictionally on an upper mounted on a last, power-operated mechanism for effecting automatically predetermined relative movement of said device and the last in a direction heightwise of the last to conform the upper tightly to the contour of the last in response to the frictional pull of said device on the upper, and fluid pressure means for operating said device thereafter to lay the marginal portion of the upper inwardly over an insole on the last and to press it upon the insole.

2. In a lasting machine, a device arranged to act frictionally on an upper mounted on a last, power-operated mechanism for effecting automatically predetermined relative movement of said device and the last heightwise of the last to draw the upper tightly over the last, and fluid pressure means automatically operative in predetermined time relation to said mechanism for progressively increasing the pressure of said device on the upper during said relative movement to increase its frictional pull on the upper and for thereafter operating it to lay the marginal portion of the upper inwardly over an insole on the last.

3. In a lasting machine, a flexible apron arranged to act frictionally on an upper mounted on a last, mechanism comprising different members for controlling said apron and last respectively and for effecting relative movement of said apron and the last in a direction heightwise of the last to draw the upper tightly over the last, and means for operating said apron by fluid pressure substantially at the completion of said relative movement to lay the marginal portion of the upper inwardly over an insole on the last and to press it upon the insole.

4. In a lasting machine, a flexible elastic apron for engaging an upper frictionally at the side of a last, mechanism comprising different members for controlling said apron and last respectively and for effecting relative movement of said apron and the last heightwise of the last to conform the upper tightly to the contour of the last by a frictional pull on the upper, and fluid pressure means for expanding said apron during said relative movement to cause it to force the upper better into conformity to the shape of the last.

5. In a lasting machine, a flexible apron for engaging an upper frictionally at the side of a last, mechanism for effecting relative movement of said apron and the last heightwise of the last to cause said apron by frictional contact with the upper to draw it tightly over the last, and fluid pressure means automatically operative in predetermined time relation to said mechanism for forcing said apron against the upper with increasing pressure during said relative movement and for thereafter operating it to lay the marginal portion of the upper inwardly over an insole on the last and to press the upper against the insole.

6. In a lasting machine, a flexible lasting member constructed and arranged to act frictionally on an upper mounted on a last and to be moved heightwise of the last to draw the upper tightly over the last before the marginal portion of the upper is laid inwardly over an insole on the last, said member being chambered and expandable by

fluid pressure and having an upper-pressing wall conformable thereby to the shape of the last and an edge portion extending above said chambered portion, and a member connected to said edge portion for imparting to said lasting member its heightwise movement.

7. In a lasting machine, a flexible elastic member for engaging an upper frictionally at the side of a last, said member being expansible by fluid pressure to conform the upper to the shape of the last, mechanism for effecting relative movement of said member and the last in a direction heightwise of the last to cause it by frictional contact with the upper to work the upper toward the bottom face of the last and for moving said member inwardly over an insole on the last only after said relative movement has been substantially completed, and fluid pressure means for expanding said member during said relative heightwise movement to increase the pressure of said member on the upper and for further expanding said member after the completion of its inward movement by said mechanism to cause it to lay the marginal portion of the upper inwardly over the insole and to press it upon the insole.

8. In a lasting machine, a flexible lasting member of elastic material arranged to receive a last presented by the operator bottom upward with an upper and an insole thereon and expansible by fluid pressure to press the upper at the sides of the last between its toe and heel-end portions into conformity to the shape of the insole, and supporting mechanism for said lasting member constructed to impart to it a movement heightwise of the last relatively to said insole-engaging means to cause said member by frictional contact with the upper to work it tightly over the last.

9. In a lasting machine, a flexible elastic apron arranged to receive a last presented by the operator bottom upward with an upper and an insole thereon and to work the upper at opposite sides of the last by frictional contact therewith heightwise of the last in response to relative movement of the apron and the last before the marginal portion of the upper is laid inwardly over the insole, said apron being chambered and expandable by fluid pressure to force the upper into conformity to the shape of the last during said relative movement, and mechanism comprising different members for controlling said apron and last respectively and for effecting said relative movement.

10. In a lasting machine, a flexible elastic apron arranged to support a last presented by the operator bottom upward with an upper and an insole thereon and to work the upper by frictional contact therewith at opposite sides of the last heightwise of the last in response to relative movement of the apron and the last, said apron being chambered and expandable by fluid pressure to conform the upper to the shape of the last during said relative movement and then to lay the marginal portion of the upper inwardly over the insole and to press it upon the insole, and means movable into position over the insole at the completion of said relative movement to confine said apron against excessive expansion in directions heightwise of the last away from the insole.

11. In a lasting machine, a flexible apron arranged to receive a last with an upper and an insole thereon and to act frictionally on the upper to work it heightwise of the last in response to relative movement of the apron and the last be-

- fore the marginal portion of the upper is laid inwardly over the insole, means for operating said apron by fluid pressure to clamp the upper to the last near the top of the last to prevent distortion of the clamped portions of the upper heightwise of the last, and separate means for operating said apron by fluid pressure to lay the marginal portion of the upper inwardly over the insole and to press it upon the insole.
10. 12. In a lasting machine, a flexible apron arranged to support a last presented by the operator bottom upward with an upper and an insole thereon and to act frictionally on the upper at opposite sides of the last to work the upper heightwise of the last in response to relative movement of the apron and the last, said apron having a chambered lower portion arranged to extend across the top face of the last and expansible by fluid pressure to clamp the upper to the sides of the last near the top of the last to prevent distortion of the clamped portions of the upper heightwise of the last and chambered upper portions extending lengthwise of the last between its toe and heel-end portions and expansible by fluid pressure to press the upper into conformity to the shape of the last during the relative movement of the apron and the last.
15. 13. In a lasting machine, a flexible lasting member of elastic material arranged to support a last presented by the operator bottom upward with an upper and an insole thereon and to engage the upper at the sides of the last between its toe and heel-end portions, said member having a chambered lower portion extending across the top face of the last and inflatable by fluid pressure to clamp the upper against the last near the top of the last and chambered upper portions inflatable by fluid pressure to press the upper into conformity to the shape of the last, and mechanism for effecting relative movement of said member and the last heightwise of the last to cause said member by frictional contact with the upper to draw it tightly over the last while holding the upper near the top of the last against distortion heightwise of the last.
20. 14. In a lasting machine, an expansible lasting member of elastic material arranged to support a last presented by the operator bottom upward with an upper and an insole thereon and to engage the upper at opposite sides of the last between its toe and heel-end portions, mechanism to which the opposite marginal portions of said lasting member are secured at the sides of the last for moving said member relatively to the last in a direction heightwise of the last to cause said member by frictional contact with the upper to draw it tightly over the last, and fluid pressure means for expanding said member substantially at the beginning of its heightwise movement to cause said member to press the upper into conformity to the shape of the last, said means being arranged progressively to increase the pressure of said member on the upper during said heightwise movement to increase its frictional pull on the upper.
25. 15. In a lasting machine, a flexible elastic apron arranged to support a last presented by the operator bottom upward with an upper and an insole thereon and to act frictionally on the upper at opposite sides of the last to work the upper heightwise of the last before the marginal portion of the upper is laid inwardly over the insole, said apron having a chambered lower portion arranged to extend across the top face of the last and expansible by fluid pressure to

clamp the upper to the sides of the last near the top of the last to prevent distortion of the clamped portions of the upper heightwise of the last, and chambered upper portions expansible independently of the lower portion to lay the marginal portion of the upper inwardly over the insole.

16. In a lasting machine, a flexible elastic apron arranged to support a last presented by the operator bottom upward with an upper and an insole thereon and to engage the upper at the sides of the last between its toe and heel-end portions, members connected to said apron at the opposite sides of the last for moving the apron heightwise of the last to cause the apron by frictional contact with the upper to draw it tightly over the last, means for engaging the bottom face of the insole to support the last against the pull of the apron, and means for operating said apron by fluid pressure to lay the marginal portion of the upper inwardly over the insole and to press it upon the insole.

17. In a lasting machine, a flexible elastic apron arranged to support a last presented by the operator bottom upward with an upper and an insole thereon and to engage the upper at the sides of the last between its toe and heel-end portions, power operated means for moving said apron heightwise of the last to draw the upper tightly over the last and for thereafter moving said apron inwardly over the insole, means arranged by engagement with the bottom face of the insole to support the last against the pull of the apron, and means for operating said apron by fluid pressure to lay the marginal portion of the upper inwardly over the insole and to press it upon the insole.

18. In a lasting machine, a flexible elastic apron arranged to support a last presented by the operator bottom upward with an upper and an insole thereon and to engage the upper at the sides of the last between its toe and heel-end portions, a pair of holddowns adjustable lengthwise of the last to accommodate lasts of different sizes and movable toward the last into engagement with the bottom face of the insole and the overlaid margin of the upper at the opposite ends of the last, means for locking said holddowns in work-engaging positions, cam-controlled means for moving said apron relatively to the last in a direction to cause said apron by frictional contact with the upper to work it heightwise of the last and for thereafter moving said apron inwardly over the insole, and means for operating said apron by fluid pressure to lay the marginal portion of the upper inwardly over the insole and to press it upon the insole.

19. In a lasting machine, a flexible elastic apron arranged to support a last presented by the operator bottom upward with an upper and an insole thereon and to engage the upper at opposite sides of the last between its toe and heel-end portions, members for engaging the bottom face of the insole and the overlaid margin of the upper at opposite ends of the last, power operated means for moving the apron relatively to said members in a direction heightwise of the last to cause said apron by frictional contact with the upper to draw it tightly over the last, said means being arranged thereafter to move the apron inwardly over the insole at opposite sides of the last, and fluid pressure means for operating said apron to lay and press the marginal portion of the upper against the insole.

20. In a lasting machine, a flexible elastic apron arranged to support a last with an upper and an

insole thereon and to act on the upper at opposite sides of the last between its toe and heel-end portions, carriers for supporting the apron at the opposite sides of the last and movable bodily upward to stretch the apron over the last to conform the upper tightly to the contour of the last, said carriers being movable also inwardly over the insole each about an axis located below the last to increase the tension of the apron about the last, abutments for supporting the last against the pull of the apron, and fluid pressure means for operating said apron to lay the marginal portion of the upper inwardly over the insole and to press it upon the insole.

21. In a lasting machine, a flexible elastic apron arranged to support a last presented by the operator bottom upward with an upper and an insole thereon and to act on the upper at opposite sides of the last between its toe and heel-end portions, members for engaging the bottom face of the insole at opposite ends of the last, a pair of levers for supporting the apron at the opposite sides of the last, power-operated means for moving said levers bodily upward to stretch the apron over the last to conform the upper tightly to the contour of the last and for thereafter swinging said levers inwardly over the insole about an axis located below the last to increase the tension of the apron about the last, and fluid pressure means for operating said apron to lay and press the margin of the upper inwardly over the insole.

22. In a lasting machine, a flexible elastic apron arranged to support a last presented by the operator bottom upward with an upper and an insole thereon and to act on the upper at the sides of the last between its toe and heel-end portions, a pair of levers mounted for swinging movements toward and from each other each about an axis located below the last for supporting the apron at the sides of the last, power-operated means for swinging said levers toward each other to carry the apron inwardly over the insole, and means for operating said apron by fluid pressure to lay the marginal portion of the upper inwardly over the insole and to press it upon the insole.

23. In a lasting machine, a pair of levers, a flexible elastic apron supported by said levers and shaped to provide a sling-like support for a last presented by the operator bottom upward with an upper and an insole thereon, said apron being arranged to act on the upper at opposite sides of the last between its toe and heel-end portions, power-operated means for moving said levers bodily upward to stretch the apron over the last to conform the upper tightly to the contour of the last and for swinging said levers toward each other to carry the apron inwardly over the insole, and means for operating said apron by fluid pressure to lay and press the margin of the upper inwardly over the insole.

24. In a lasting machine, a flexible elastic apron arranged to support a last presented by the operator bottom upward with an upper and an insole thereon and to act on the upper at the sides of the last between its toe and heel-end portions, a pair of levers mounted for swinging movements toward and from each other each about an axis located below the last for supporting the apron at the sides of the last, power-operated means for moving said levers bodily upward to stretch the apron over the last to conform the upper tightly to the contour of the last, a holddown for supporting the last against the pull of the apron, cam-controlled means for swinging said levers toward each other at the completion of their upward

movements to carry the apron inwardly over the insole, and means for operating said apron by fluid pressure to lay the marginal portion of the upper inwardly over the insole and to press it upon the insole.

25. In a lasting machine, a flexible elastic apron arranged to support a last presented by the operator bottom upward with an upper and an insole thereon and to act on the upper at the sides of the last between its toe and heel-end portions, holddowns for engaging the bottom face of the insole and the overlaid margin of the upper at opposite ends of the last, a pair of levers mounted for swinging movements toward and from each other each about an axis located below the last for supporting the apron at the sides of the last, toggles for imparting to said levers their swinging movements, power-operated means for moving said levers bodily upward to stretch the apron over the last to conform the upper tightly to the contour of the last, cam-controlled means for operating said toggles to swing the levers toward each other to carry the apron inwardly over the insole, and means for operating said apron by fluid pressure to lay the marginal portion of the upper inwardly over the insole and to press it upon the insole.

26. In a lasting machine, an expansible lasting member of elastic material arranged to extend across the top face of a last with an upper and an insole thereon and to engage the upper at opposite sides of the last between its toe and heel-end portions, mechanism for effecting relative movement of said lasting member and the last heightwise of the last to cause said lasting member to draw the upper tightly over the last and for thereafter moving said lasting member inwardly over the insole, means movable with said lasting member into position over the insole to confine said lasting member against excessive expansion in directions heightwise of the last away from the insole, and fluid pressure means for expanding said lasting member during said relative heightwise movement to increase its pressure on the upper and for thereafter further expanding said lasting member after it has been moved inwardly over the insole to cause it to press the marginal portion of the upper upon the insole.

27. In a lasting machine an expansible lasting member of elastic material arranged to support a last presented by the operator bottom upward with an upper and an insole thereon and to extend lengthwise of the last between its toe and heel-end portions, carriers for supporting said lasting members at the sides of the last and movable relatively to the last to stretch the lasting member over the last in a direction to work the upper heightwise of the last, said carriers being movable also toward each other to move the lasting member inwardly over the insole, members arranged to be moved into interlocking relation to each other by the inward movement of the carriers to confine said lasting member against excessive expansion in directions heightwise of the last away from the insole, and fluid pressure means for expanding said lasting member to cause it to press the marginal portion of the upper upon the insole.

28. In a lasting machine, an expansible lasting member of elastic material arranged to support a last bottom upward with an upper and an insole thereon and to extend lengthwise of the last between its toe and heel-end portions, carriers for supporting said lasting member at the

- sides of the last, power operated means for moving said carriers to stretch the lasting member over the last to work the upper heightwise of the last and for thereafter moving said carriers 5 toward each other to move the upper portions of the lasting member at opposite sides of the last inwardly over the insole, members arranged to be moved into interlocking relation with each other by the inward movement of the carriers 10 to confine the inwardly disposed upper portions of said lasting member against excessive expansion in directions heightwise of the last away from the insole, and fluid pressure means for expanding said lasting member to cause it to 15 press the marginal portion of the upper upon the insole.
29. In a lasting machine, a flexible lasting member of elastic material arranged to extend across the top face of a last with an upper and 20 an insole thereon and to engage the upper at opposite sides of the last between its toe and heel-end portions, said member being expansible by fluid pressure to press the upper into conformity to the shape of the last, means for 25 effecting relative movement of said member and the last heightwise of the last to cause said member by frictional contact with the upper to work the upper tightly over the last, and means for controlling the admission and exhaust of 30 pressure fluid to and from said member.
30. In a lasting machine, an expansible lasting member of flexible elastic material arranged to extend across the top face of a last with an upper and an insole thereon and to engage the 35 upper at the sides of the last between its toe and heel-end portions, fluid pressure means for expanding said lasting member to conform the upper to the shape of the last, cam-controlled means for effecting relative movement of said 40 lasting member and the last heightwise of the last to cause said member by frictional contact with the upper to draw it tightly over the last, and means operating in time relation to said last-named means for connecting said fluid pressure 45 means to said lasting member substantially at the beginning of such relative movement.
31. In a lasting machine, an expansible lasting member of flexible elastic material arranged to extend across the top face of a last with an 50 upper and an insole thereon and to engage the upper at the sides of the last between its toe and heel-end portions, a holddown for engaging the bottom face of the insole, power operated means for moving said lasting member relative- 55 ly to said holddown heightwise of the last to draw the upper tightly over the last, fluid pressure means for expanding said lasting member to conform it to the shape of the last and to cause it to lay the marginal portion of the upper 60 inwardly over the insole and to press it upon the insole, and means arranged to act automatically to connect said fluid pressure means to said lasting member substantially at the beginning of its heightwise movement.
- 65 32. In a lasting machine, an expansible lasting member of flexible elastic material arranged to extend across the top face of a last with an upper and an insole thereon and to engage the upper at the sides of the last between its toe and heel-end 70 portions, a holddown for engaging the bottom face of the insole at opposite ends of the last, cam-controlled means for imparting to said lasting member a movement heightwise of the last to cause it by frictional contact 75 with the upper to draw the upper tightly over the last and for thereafter moving said lasting member inwardly over the insole, fluid pressure means for expanding said lasting member to increase its pressure on the upper and to cause it to lay the marginal portion of the upper inwardly 5 over the insole and to press it upon the insole, automatic means for connecting said fluid pressure means to said lasting member, and a valve adjustable to regulate the flow of pressure fluid 10 to the lasting member.
33. In a lasting machine, a flexible lasting member arranged to support a last presented by the operator bottom upward with an upper and an insole thereon, said lasting member being expansible by fluid pressure to conform the upper to the contour of the last, mechanism for moving said member relatively to the last in a direction heightwise of the last to draw the upper tightly over the last, and automatic means for supplying pressure fluid to said member in 15 time relation to its heightwise movement.
34. In a lasting machine, flexible lasting means arranged to act frictionally on an upper at opposite sides of a last to work the upper heightwise of the last before its marginal portion is 20 laid inwardly over an insole on the last, said means being expansible by fluid pressure to press the upper into conformity to the contour of the last, fluid pressure means for expanding said lasting means, automatic means for controlling the 25 admission of pressure fluid to said lasting means, and means for adjustably varying the flow of 30 said pressure fluid.
35. In a lasting machine, a flexible lasting member arranged to support a last presented by the operator bottom upward with an upper and an insole thereon and to act on the upper at the sides of the last between its toe and heel-end 35 portions, said member being expansible by fluid pressure to press the upper against the last to 40 conform it to the shape of the last, mechanism for effecting relative movement of said member and the last heightwise of the last to cause said member by frictional contact with the upper to draw it tightly over the last, and means for sup- 45 plying pressure fluid to said member.
36. In a lasting machine, a flexible lasting member arranged to act frictionally on an upper at opposite sides of a last to work the upper heightwise of the last before its marginal portion 50 is laid inwardly over an insole on the last, said member being expansible by fluid pressure to press the upper into conformity to the contour of the last, automatic means for admitting pressure fluid to said member and for releasing it 55 therefrom, and adjustable means for varying the flow of said pressure fluid.
37. In a lasting machine, a flexible lasting member arranged to support a last presented by the operator bottom upward with an upper and an insole thereon and to act on the upper at the sides of the last between its toe and heel-end 60 portions, said lasting member being expansible by fluid pressure to conform the upper to the contour of the last, mechanism for moving said member relatively to the last in a direction heightwise of the last to draw the upper tightly over the last, and automatic means for supplying pressure fluid to said member substantially at 65 the beginning of its heightwise movement.
38. In a lasting machine, a flexible lasting member arranged to act frictionally on an upper to work the upper heightwise of a last, said member being expansible by fluid pressure to press the upper against the last to conform it to the 70 75

shape of the last while working the upper over the last, a valve for admitting pressure fluid to said member, and automatic means for opening said valve.

5 39. In a lasting machine, an expansible lasting member of elastic material arranged to act frictionally on an upper at the sides of a last to work the upper heightwise of the last, fluid pressure means for expanding said member to conform the upper to the shape of the last and for thereafter further expanding said member to cause it to lay the marginal portion of the upper inwardly over an insole on the last, a valve for controlling the flow of pressure fluid, and automatic means for opening said valve.

40. In a lasting machine, a flexible lasting member of elastic material arranged to act frictionally on an upper at the sides of a last to work the upper heightwise of the last in response to relative movement of the member and the last, said member being expansible by fluid pressure to force the upper into conformity to the shape and the last during said relative movement and thereafter to lay its marginal portion inwardly over an insole on the last and to press it upon the insole, means for supplying pressure fluid to said lasting member, and a valve for regulating the flow of pressure fluid from said supply means to the lasting member.

30 41. In a lasting machine, a flexible lasting member of elastic material arranged to act frictionally on an upper at the sides of a last to work the upper heightwise of the last and expandable by fluid pressure to press the upper into conformity to the shape of the last and then to lay its marginal portion inwardly over an insole on the last and to press it upon the insole, a valve for supplying pressure fluid to said member, means for opening said valve, and a second

valve for regulating the flow of pressure fluid to the lasting member.

42. In a lasting machine, a flexible lasting member of elastic material arranged to engage an upper frictionally at the side of a last and to work the upper heightwise of the last in response to relative movement of the member and the last, said member being expansible by fluid pressure to press the upper into conformity to the contour of the last and to lay its marginal portion inwardly over an insole on the last and to press it upon the insole, a conduit connected to said lasting member, a second conduit connected to a source of supply of pressure fluid, means for connecting said conduits, a valve at the point of connection for controlling the flow of pressure fluid, and means for opening said valve when the connection has been established.

43. In a lasting machine, a flexible lasting member of elastic material arranged to engage an upper frictionally at the side of a last and to work the upper heightwise of the last in response to relative movement of the member and the last, said member being expansible by fluid pressure to lay the marginal portion of the upper inwardly over an insole on the last and to press it upon the insole, a conduit connected to said lasting member, a second conduit connected to a source of supply of pressure fluid, means for connecting said conduits, a valve at the point of connection for controlling the flow of pressure fluid from said source of supply, means for opening said valve when the connection has been established, and a second valve adjustable to regulate the flow of pressure fluid to said lasting member.
